US0D1044411S

(12) **United States Design Patent** (10) Patent No.: **US D1,044,411 S**
(45) Date of Patent: ** Oct. 1, 2024

(54) **BOTTLE WITH CLOSURE**

(71) Applicant: **ISi GmbH**, Vienna (AT)

(72) Inventor: **Dominik Meier**, Munich (DE)

(73) Assignee: **ISi GmbH**, Vienna (AT)

(**) Term: **15 Years**

(21) Appl. No.: **35/515,890**

(22) Filed: **Dec. 9, 2022**

(80) **Hague Agreement Data**

Int. Filing Date: **Dec. 9, 2022**

Int. Reg. No.: **DM/225738**

Int. Reg. Date: **Dec. 9, 2022**

Int. Reg. Pub. Date: **Dec. 30, 2022**

(30) **Foreign Application Priority Data**

Jun. 15, 2022 (AT) ..... MU 17/2022

(51) **LOC (14) Cl.** **07-01**

(52) **U.S. Cl.**

USPC **D7/511; D9/553**
